(57) **CLAIM**

The ornamental design for a face mask, as shown and described.

DESCRIPTION

FIG. 1 is a perspective view of a face mask;
FIG. 2 is a top plan view of the face mask of FIG. 1;
FIG. 3 is a front view of the face mask of FIG. 1;
FIG. 4 is a rear view of the face mask of FIG. 1;
FIG. 5 is a side view of the face mask of FIG. 1; and,
FIG. 6 is another side view of the face mask of FIG. 1.
The broken lines illustrating a figure wearing the face mask depicts environmental subject matter that forms no part of the claimed design.
